SWITCH EMPLOYING DAMPING MEANS FOR CONTROLLING MOVEMENT OF ITS BRIDGING ELEMENTS

Joseph M. Ramrath, Mattapan, Mass., assignor to Allis-Chalmers Manufacturing Company, Milwaukee, Wis.

Application December 5, 1956, Serial No. 626,429

9 Claims. (Cl. 200—170)

This invention relates to electric current interrupters and more particularly to a new and improved switch employing contact damping means.

It is well known in the art of electric circuit interrupters that if cooperating separable contacts are rigid metallic elements any appreciable misalignment between the contact surfaces due to inaccuracies of manufacture or assembly or due to wear results in unequal pressure distribution throughout the contact surface and in extreme conditions single point contact. In oil circuit breakers the contacts are subject to thermal and dynamic stresses in keeping with the high circuit breaker ratings and high speed switch operations. In order to withstand the high inrush current under short circuit conditions and to insure equal current distribution throughout all of the contact elements to avoid pitting of the contact surfaces a great number of contact points must be made. Experience has taught that the lower limit of the width of finger contacts is about $\frac{5}{32}$ of an inch. If a plurality of finger contacts of this width are to be used to constitute the connecting means in a blade finger contact structure, springing of the fingers becomes a problem. Another difficulty encountered is the repulsive force that tries to push the contact fingers apart when the blade is brought into engagement with the fingers at closing in on short circuit. This difficulty is increased by the mechanical movement of the blade at high closing speeds resulting in a mechanical throwoff force of the fingers. The combination of the repulsive force and the throwoff force of this type of contact structure may cause severe burning of the contact surfaces and after a few operations result in the destruction of the contact structure.

In accordance with the invention claimed a new and improved electric switch structure is provided comprising a pair of cooperating relatively movable contact elements each having a contact surface and a plurality of rigid conducting bridging elements. The bridging elements are disposed to engage the surfaces of the contact elements in circuit closing position of the switch. Spring biasing means are disposed to bias the bridging elements into engagement with the contact elements and a resilient mat is interposed between the spring biasing means and the bridging elements for procuring substantially equal contact pressure at all points of contact during switch closing operations by damping the movement of the bridging elements.

It is, therefore, one subject of this invention to provide a new and improved electric switch.

Another object of this invention is to provide a new and improved electric switch employing a plurality of finger contact elements in which substantially equal contact pressure is provided at all points of contact during switch closing operations by damping the movement of the bridging contact elements.

A further object of this invention is to provide a new and improved switch employing separable contacts which

2

is substantially unaffected by the forces occasioned by short circuits or substantial overloads in a circuit in which the switch is connected.

A still further object of this invention is to provide a new and improved circuit interrupter which is simple, reliable and flexible in operation, rugged in structure and economical to manufacture.

Objects and advantages other than those set forth will be apparent from the following description when read in connection with the accompanying drawing, in which:

Fig. 1 is a front view in cross section of a switch structure taken along the line I—I of Fig. 2 and embodying the invention;

Fig. 2 is a cross sectional right end view of the structure shown in Fig. 1 taken along the line II—II;

Fig. 3 is a cross sectional view of Fig. 1 taken along the line III—III.

Referring more particularly to the drawing by characters of reference, Figs. 1, 2 and 3 illustrate an electric switch 10 comprising a U-shaped relatively stationary current conductive contact 11 and a cooperating movable current conductive contact 12. The U-shaped stationary contact 11 comprises a pair of legs 13 and 14 which may be, for example, parallelly arranged and interconnected by a bight 15 defining a protrusion 16. Protrusion 16 extends from bight 15 between legs 13 and 14 for supporting a pair of, for example, parallelly arranged opposed contact surfaces 17. The movable contact 12 is provided with a projecting blade having a pair of, for example, opposed parallelly arranged contact surfaces 18. The contact elements 11 and 12 are normally symmetrical about a common plane including their longitudinal axes.

Supported from the legs 13 and 14 of the stationary contact 11 are a pair of side members 19 and 20 secured thereto by suitable bolts 21 extending from end plates 30 and 31. The stationary contact 11 and its side members 19 and 20 combine to form a rigid box-like structure for enclosing the movable parts of switch 10. Extending between legs 13 and 14 one on each side of protrusion 16 and arranged substantially parallel with side members 19 and 20 are a pair of pivot pins 22 and 23 upon which are disposed or mounted a plurality of rigid conducting bridging elements 24. Bridging elements 24 are provided with arcuate contact surfaces near each end of each element and so disposed, as illustrated in Fig. 1, when in switch closed position to engage edgewise the opposing contact surfaces 17 and 18 of contact elements 11 and 12, respectively. The bridging elements 24 may be punched blades or laminations or any suitable rigid conducting elements.

The opposed finger contact members or bridging elements 24 are biased toward each other and protrusion 16 and thus into pressure engagement with the opposed contact surfaces of the contact elements 11 and 12 by suitable biasing means such as springs 25. Springs 25 are each disposed between one of the legs of the U-shaped contact element 11 and protrusion 16 and are each loosely arranged within a different aperture 26 formed in the juxtaposed surfaces of side members 19 and 20. The position and manner in which these biasing springs are assembled is shown in detail in Figs. 1, 2 and 3. Springs 25 are given suitable compression by means of end plates 30 and 31 and bolts 21.

In accordance with the invention claimed resilient mats 27 of suitable material such as rubber or plastic are interposed between the springs 25 and the bridging elements 24 on each side of protrusion 16. Each mat 27 is fastened to a different one of the side members 19 and 20 by bolts 28 at the ends thereof adjacent to pro-

trusion 16, and form by reason of the resiliency of the mat a pivotal connection. The purpose of mats 27 is to establish a uniform pressure over the current carrying bridging fingers or elements 24, making use of the sponginess of the rubberlike material to fill in any unevenness of the surface formed by the back edges of the bridging elements. Mats 27 also act as a means to provide ample damping of the movement of the bridging elements during a switch closing operation.

If switch 10 is used in a bath of fluid such as oil and the switch is closed by blade 12 wedging in between bridging elements 24, oil trapped under mats 27 may leave only at the lower or open end of the switch, as shown in Fig. 1. Mats 27, as shown in Fig. 3, are wide enough to extend completely across the back of the bridging elements and oil trapped between mats 27 and side members 19 and 20 by reason of the fact that mats 27 are held away from legs 13 and 14 a predetermined distance at their free ends by springs 25 is forced out from between mats 27 and legs 13 and 14 by the outward movement of the bridging elements 24 during a switch closing operation. The oil dampens the outward movement of the bridging elements to prevent the bridging elements 24 from losing contact with the movable contact 12 during contact opening or closing operations. In this manner the springing movement of the bridging elements is greatly reduced or satisfactorily controlled. Also, the difficulty encountered by the repulsive forces pushing the bridging elements away from the movable blade contact 12 when closing the switch on a shorted circuit is damped or controlled by the switch structure described and claimed.

In order to control the inward movement of the bridging elements 24 during a switch opening operation and to retain the lower ends of the bridging elements apart a predetermined distance in switch open position each bridging element is provided with a surface 29 for abutting the side members 19 or 20 depending on which side of protrusion 18 the bridging element is mounted. Thus, as the switch opens springs 25 bias the opposing bridging elements toward each other and they move toward each other until surfaces 29 engage side members 19 and 20.

When switch 10 is closed by the wedge movement of contact element 12 between the bridging elements 24 the bridging elements are pivoted away from contact element 12 forcing oil or air, depending on the medium in which it operates, out from under mats 27. The bridging elements because of the damping action cling to the movable contact element 12, thus eliminating severe burning of the contact surface usually occurring with switches not provided with a suitable bridging element damping means.

While the invention has been applied to a switch structure employing a plurality of pairs of opposed bridging elements 24, it will be apparent that any desired number of bridging elements may be employed and disposed on one or both sides of the stationary contact.

Although but one embodiment of the present invention has been illustrated and described, it will be apparent to those skilled in the art that various changes and modifications may be made herein without departing from the spirit of the invention or from the scope of the appended claims.

What is claimed is:

1. In an electric switch the combination comprising a pair of cooperating relatively movable contact elements each having contact surfaces, a plurality of rigid conducting bridging elements, said elements being disposed to engage said surfaces of said contact elements in circuit closing position of said switch, spring biasing means disposed to bias said bridging elements into engagement with said contact elements, and a resilient mat secured at one end to one of said contact elements and interposed along its length between said spring biasing means and said bridging elements for procuring sub-

stantially equal contact pressure at all points of contact during switch closing operations by damping the movement of said bridging elements.

2. In an electric switch the combination comprising a pair of cooperating relatively movable contact elements each having opposed contact surfaces, a plurality of pairs of rigid conducting bridging elements, the elements of each pair being disposed to engage opposing surfaces of said contact elements in circuit closing position of said switch, spring biasing means disposed to bias said bridging elements into engagement with said contact elements, and a resilient mat secured at one end to one of said contact elements and interposed along its length between said spring biasing means and said bridging elements for procuring substantially equal contact pressure at all points of contact during switch closing operations by damping the movement of said bridging elements.

3. In an electric switch the combination comprising a U-shaped relatively stationary contact element and a cooperating relatively movable contact element each having contact surfaces, said U-shaped contact element comprising a pair of spaced legs interconnected by a bight and defining a protrusion extending from said bight between said legs for supporting said contact surfaces on said stationary contact, a plurality of rigid conducting bridging elements, said elements being disposed between said legs to engage said surfaces of said U-shaped contact element and said surfaces of said movable contact element in circuit closing position of said switch, spring biasing means disposed between one of said legs and said protrusion to bias said bridging elements into engagement with said stationary contact element and said movable contact element, and a resilient mat interposed between said spring biasing means and said bridging elements for procuring substantially equal contact pressure at all points of contact during switch closing operations by damping the movement of said bridging elements.

4. In an electric switch the combination comprising a U-shaped relatively stationary contact element and a cooperating relatively movable contact element each having opposed contact surfaces, said U-shaped contact element comprising a pair of spaced legs interconnected by a bight and defining a protrusion extending from said bight between said legs for supporting said opposed contact surfaces on said stationary contact, a pair of rigid conducting bridging elements, said elements being disposed between said legs one on each side of said protrusion for engaging opposing surfaces of said U-shaped contact element and said movable element in circuit closing position of said switch, a pair of spring biasing means each disposed between one of said legs and said protrusion to bias said bridging elements into engagement with said stationary contact element and said movable contact element, and a pair of resilient mats one interposed between each of said spring biasing means and said bridging elements on a different side of said protrusion for procuring substantially equal contact pressure at all points of contact during switch closing operations by damping the movement of said bridging elements.

5. In an electric switch the combination comprising a U-shaped relatively stationary contact element and a cooperating relatively movable contact element each having opposed contact surfaces, said U-shaped contact element comprising a pair of spaced legs interconnected by a bight and defining a protrusion extending from said bight between said legs for supporting said opposed contact surfaces on said stationary contact, a pair of rigid conducting bridging elements, said elements being disposed between said legs one on each side of said protrusion for engaging opposing surfaces of said U-shaped contact element and said movable contact element in circuit closing position of said switch, a pair of spring biasing means each disposed between one of said legs and said protrusion to bias said bridging elements into engagement with said

stationary contact element and said movable contact element, and a pair of resilient mats each pivotally mounted at one end thereof to a different one of said legs and interposed between said spring biasing means and said bridging elements for procuring substantially equal contact pressure at all points of contact during switch closing operations by damping the movement of said bridging elements.

6. In an electric switch the combination comprising a U-shaped relatively stationary contact element and a cooperating relatively movable contact element each having opposed contact surfaces, said U-shaped contact element comprising a pair of spaced parallelly arranged legs interconnected by a bight and defining a protrusion extending from said bight between said legs for supporting said opposed contact surfaces on said stationary contact, a plurality of pairs of rigid conducting bridging elements, the elements of each pair being disposed between said legs one on each side of said protrusion for engaging opposing surfaces of said U-shaped contact element and said movable contact element in circuit closing position of said switch, a plurality of spring biasing means each disposed between one of said legs and said protrusion to bias said bridging elements into engagement with said stationary contact element and said movable contact element, and a pair of resilient mats one arranged on each side of said protrusion and interposed between said spring biasing means and said bridging elements for procuring substantially equal contact pressure at all points of contact during switch closing operations by damping the movement of said bridging elements.

7. In an electric switch the combination comprising a U-shaped relatively stationary contact element and a cooperating relatively movable contact element each having opposed contact surfaces, said U-shaped contact element comprising a pair of spaced parallelly arranged legs interconnected by a bight and defining a protrusion extending from said bight between said legs for supporting said opposed contact surfaces on said stationary contact, a plurality of pairs of rigid conducting bridging elements, the elements of each pair being disposed between said legs one on each side of said protrusion for engaging opposing surfaces of said U-shaped contact element and said movable contact element in circuit closing position of said switch, a plurality of spring biasing means each disposed between one of said legs and said protrusion to bias said bridging elements into engagement with said stationary contact element and said movable contact element, and a pair of resilient mats each pivotally mounted at one end thereof to a different one of said legs and interposed between said spring biasing means and said bridging elements for procuring substantially equal contact pressure at all points of contact during switch closing operations by damping the movement of said bridging elements.

8. In an electric switch the combination comprising a U-shaped relatively stationary contact element and a cooperating relatively movable contact element each hav-

ing opposed contact surfaces, said U-shaped contact element comprising a pair of spaced parallelly arranged legs interconnected by a bight and defining a protrusion extending from said bight between said legs for supporting said opposed contact surfaces on said stationary contact, each of said legs defining a plurality of apertures arranged in their juxtaposed surfaces, a plurality of pairs of rigid conducting bridging elements, the elements of each pair being disposed between said legs one on each side of said protrusion for engaging opposing surfaces of said U-shaped contact element and said movable contact element in circuit closing position of said switch, a plurality of springs each arranged within a different one of said apertures and between one of said legs and said protrusion to bias said bridging elements into engagement with said stationary contact element and said movable contact element, and a pair of resilient mats each pivotally mounted at one end thereof to a different one of said legs and interposed between said springs and said bridging elements for procuring substantially equal contact pressure at all points of contact during switch closing operations by damping the movement of said bridging elements.

9. An electric switch for operation within a fluid comprising in combination a U-shaped relatively stationary contact element and a cooperating relatively movable contact element each having opposed contact surfaces, said U-shaped contact element comprising a pair of spaced parallelly arranged legs interconnected by a bight and defining a protrusion extending from said bight between said legs for supporting said opposed contact surfaces on said stationary contact, a plurality of pairs of rigid conducting bridging elements, the elements of each pair being disposed between said legs one on each side of said protrusion for engaging opposing surfaces of said U-shaped contact element and said movable contact element in circuit closing position of said switch, a plurality of spring biasing means each disposed between one of said legs and said protrusion to bias said bridging elements into engagement with said stationary contact element and said movable contact element, and a pair of resilient mats each pivotally mounted at one end thereof to a different one of said legs and interposed between said springs and said bridging elements for procuring substantially equal contact pressure at all points of contact during switch closing operations by damping the movement of said bridging elements.
